US00D717708S

(12) **United States Design Patent**
Romero et al.

(10) **Patent No.:** US D717,708 S
(45) **Date of Patent:** ** Nov. 18, 2014

(54) **VEHICULAR SIDE BAR FOOT STEP**

(71) Applicants: **Rigoberto Gonzalez Romero**, Zapopan (MX); **Alberto Montoya Aguilar**, Zapopan (MX)

(72) Inventors: **Rigoberto Gonzalez Romero**, Zapopan (MX); **Alberto Montoya Aguilar**, Zapopan (MX)

(73) Assignee: **Iddea California, LLC**, Brea, CA (US)

(**) Term: **14 Years**

(21) Appl. No.: **29/433,719**

(22) Filed: **Oct. 4, 2012**

(51) LOC (10) Cl. **12-16**

(52) U.S. Cl.

USPC **D12/203**

(58) **Field of Classification Search**

USPC D12/89, 203, 314; 182/64.1, 127; 280/5.3, 163, 164.2, 166, 169, 291; D25/62, 63, 68, 69

(57) **CLAIM**

The ornamental design of the vehicular side bar foot step, as shown and described.

DESCRIPTION

FIG. 1 is a perspective view of the vehicular side bar foot step of the present invention showing my new design;

FIG. 2 is a top plan view thereof;

FIG. 3 is a rear elevational view thereof;

FIG. 4 is a bottom plan view thereof;

FIG. 5 is a rear elevational view thereof;

FIG. 6 is an end view thereof; and,

FIG. 7 is a bottom perspective view thereof.

The broken lines in the drawings illustrate the environment of the vehicular side bar foot step and form no part of the claimed design.

1 Claim, 2 Drawing Sheets
